[57] CLAIM

The ornamental design for a golfer's wallet, as shown and described.

DESCRIPTION

FIG. 1 is a front perspective view of a golfer's wallet showing my new design;

FIG. 2 is a rear view thereof, in its closed state;

FIG. 3 is a plan view of the exterior of said wallet;

FIG. 4 is a plan view of the interior of said wallet;

FIG. 5 is a plan view of the interior of said wallet with a pocket flap uplifted; and,

FIG. 6 is a top view of the wallet as shown in FIG. 4. The broken line showing of a carrying ring in FIG. 1 is for illustrative purposes only and forms no part of the claimed design.

FIG. 1

FIG. 2

FIG. 3

FIG. 4

FIG. 5

FIG. 6
